CLAIM

I claim the ornamental design for a tool chest, as shown and described.

DESCRIPTION

FIG. 1 is a perspective view of a tool chest of the new design;

FIG. 2 is a front elevation view of the tool chest of FIG. 1; FIG. 3 is a rear view of the tool chest of FIG. 1; FIG. 4 is a left side view of the tool chest of FIG. 1; FIG. 5 is a right side view of the tool chest of FIG. 1; FIG. 6 is a top view of the tool chest of FIG. 1; and, FIG. 7 is a bottom view of the tool chest of FIG. 1.

The phantom lines at the rear edge of the claimed subject matter indicate boundary of claimed design. All other phantom lines are illustrative of environment. In neither case do the phantom lines form part of the claimed design.
